UNITED STATES PATENT OFFICE

WILL CAMERON McCARTNEY, OF CAMBRIDGE, OHIO

DESIGN FOR A GLASS BOWL OR SIMILAR ARTICLE

Application filed February 3, 1930. Serial No. 34,389. Term of patent 7 years.

To all whom it may concern:

Be it known that I, WILL CAMERON McCARTNEY, a citizen of the United States of America, and resident of Cambridge, county of Guernsey, and State of Ohio, have invented a new, original, and ornamental Design for a Glass Bowl or Similar Article, of which the following is a specification, reference being had to the accompanying drawing, in which—

Figure 1 is a perspective view of a glass bowl or similar article, showing my new design; and

I claim:—

The ornamental design for a glass bowl or similar article, substantially as shown.

WILL CAMERON McCARTNEY.
